FIG22

FIG.23

FIG. 1 is a top plan view of a handle for a household appliance or similar article showing my new design;

FIG. 2 is a side elevational view thereof;

FIG. 3 is a rear view thereof;

FIG. 4 is a cross-sectional view taken on line 4—4 of FIG. 1;

FIG. 5 is a cross-sectional view taken on line 5—5 of FIG. 1;

FIG. 6 is a cross-sectional view taken on line 6—6 of FIG. 1;

FIG. 7 is a cross-sectional view taken on line 7—7 of FIG. 1;

FIG. 8 is a top plan view of a handle for a household appliance or similar article showing another form of my new design wherein the upper and lower portions are elongated from the form shown in FIG. 1;

FIG. 9 is a side edge view of a device shown in FIG. 8;

FIG. 10 is a rear view thereof;

FIG. 11 is a cross-sectional view taken on line 11—11 of FIG. 8;

FIG. 12 is a cross-sectional view taken on line 12—12 of FIG. 8;

FIG. 13 is a cross-sectional view taken on line 13—13 of FIG. 8;

FIG. 14 is a cross-sectional view taken on line 14—14 of FIG. 8;

FIG. 15 is a top plan view of a handle for a household appliance or similar article showing another form of my new design wherein the upper and lower portions are elongated from the form shown in FIG. 1;

gated approximately one-half and the width is reduced approximately one-third from the form shown in FIG. 1;

FIG. 16 is a side elevational view of the device shown in FIG. 15;

FIG. 17 is a rear view of the device shown in FIG. 15;

FIG. 18 is a cross-sectional view taken on line 18—18 of FIG. 15;

FIG. 19 is an outer end view of the device shown in FIG. 15;

FIG. 20 is a cross-sectional view taken on line 20—20 of FIG. 15;

FIG. 21 is a cross-sectional view taken on line 21—21 of FIG. 15;

FIG. 22 is a cross-sectional view taken on line 22—22 of FIG. 15; and

FIG. 23 is a cross-sectional view taken on line 23—23 of FIG. 15.

I claim:

The ornamental design for a handle for a household appliance or similar article, substantially as shown and described.
